UNITED STATES PATENT OFFICE.

JOHN N. SLAUGHENHAUP, OF CHAMBERSBURG, PENNSYLVANIA.

STRAW-CUTTER.

SPECIFICATION forming part of Letters Patent No. 292,263, dated January 22, 1884.

Application filed June 13, 1883. (No model.)

To all whom it may concern:

Be it known that I, JOHN N. SLAUGHENHAUP, a citizen of the United States, residing at Chambersburg, in the county of Franklin and State of Pennsylvania, have invented certain new and useful Improvements in Straw-Cutters, of which the following is a specification, reference being had therein to the accompanying drawings.

10 My invention relates to certain new and useful improvements in straw-cutters or stalk and hay cutters, and is an improvement on the invention described in my former patent, No. 273,619, issued March 6, 1883.

15 The object of my invention is to cut the stalks evenly and smooth, deliver the cut parts into a receptacle without loss or waste, and at the same time prevent the outer ends of the material from falling obliquely against the machine and clogging the knife.

20 I accomplish these objects by means of the peculiar construction and arrangement of the various parts, which will be more fully pointed out in the specification and claim, reference being had to the drawings accompanying this application and forming a part of the same, in which—

25 Figure 1 is a perspective view of my invention, showing the frame, box, knife, spout, and lever. Fig. 2 is a vertical sectional view of the same.

30 Similar letters refer to similar parts throughout the drawings.

Referring to the drawings, A represents a 35 box with a contracted front, mounted on standards *a* and *b*. The front of the box A is provided with a sloping cover, A', adapted to compress the material as it is fed forward under the knife. Standards *a* are provided with 40 channels or recesses *b'* on their inner faces, within which the outer edges of gate B move in its vertical ascent and descent. An inclined knife, E, is secured in gate B, and said knife is adapted to move close against the 45 metal edge of the bottom of box A. A metal strip, B', is secured across the outer face of gate B, having a projecting pin, *a'*, adapted to enter a perforation in lever C, one end of which is rounded to form a handle, and the 50 opposite end is connected by rod C' to one of the standards *a*.

Between the standards *a* is secured, by means of metal brackets *e*, a chute or spout, D. Said chute is provided with sides *c'*, and its inner end is turned up at an angle to form 55 a guide or rest, D', against which the lower surfaces of the material being cut rest while the knife E is descending, which prevents the material from bending down obliquely, and thus permits the knife E to pass over without 60 cutting. The chute or spout D is formed of one piece of metal, (preferably cast,) and is provided with a stay-brace, *d'*, one end of which is secured to the under face of said spout, and the opposite end is secured to a 65 cross-bar, *d''*. A rear standard, *b*, is secured to the under side of box A, and is provided near its foot with a stay-bar, *c*, the opposite end of which is secured to a cross-bar, *d*, connecting the feet of the standards *a*. One corner of the part D' of the spout D is turned outward slightly, to permit the knife E to pass 70 freely between the same and the edge of the bottom of box A.

The operation of the device is as follows: 75 Material is fed through the box A under the knife E, when the operator, pressing down on lever C, forces the knife E through the material—stalks, straw, or hay—down between the part D' and the edge of box A, when the short 80 pieces that are cut off from the material drop into the spout D and are delivered into a receptacle without waste.

I am aware that machines of this character are well known, and that my improvements 85 on such machines consist in the special means claimed.

Having thus described my invention, what I desire to secure by Letters Patent is—

In a stalk and straw cutting machine of the 90 character hereinbefore described, the combination, with the cutting devices, of the inclined spout D, provided with vertical rest D' and sides *c'*, said spout being secured to the posts *a* in the manner shown.

95 In testimony whereof I affix my signature in presence of two witnesses.

JOHN N. SLAUGHENHAUP.

Witnesses:

E. G. ETTER,

D. K. WUNDERLICH.
